UNITED STATES PATENT OFFICE.

EDGAR B. RUFF, OF KITTANNING, PENNSYLVANIA.

LUGGAGE-CARRIER.

1,221,909.

Specification of Letters Patent. Patented Apr. 10, 1917.

Application filed June 3, 1915. Serial No. 31,943.

To all whom it may concern:

Be it known that I, EDGAR B. RUFF, a citizen of the United States, residing at Kittanning, in the county of Armstrong and State of Pennsylvania, have invented certain new and useful Improvements in Luggage-Carriers, of which the following is a specification.

This invention relates to luggage carriers of that type which are particularly adapted to be secured rearwardly of automobiles, motorcycles, delivery wagons and the like vehicles in which an extra space for the stowage of various sized articles is desirable.

As a principal object, this invention contemplates the provision of a luggage carrier which may be secured directly to the back of the vehicle body, which may be removably braced in its extended position and which may be folded up into the smallest possible compass when not in use.

It is also a particular object of this invention to provide a luggage carrier of the type set forth which may be economically constructed entirely from metal strips in such a manner as to be both ornamental when placed upon an automobile and as to be durable and efficient in service.

The above and additional objects which will become apparent as this explanatory description proceeds, are accomplished by such means as are illustrated in the accompanying drawings, described in the following specification and then more particularly pointed out in the claims which are appended hereto and form a part of this application.

With reference to the drawings, wherein there is illustrated the preferred embodiment of this invention as it is reduced to practice, and throughout the several views of which like characters of reference designate similar parts:

Figure 1 is a rear elevation of the device in its folded position and secured directly to the body of the vehicle;

Fig. 2 is a view showing the device in plan and fully extended;

Fig. 3 is a vertical sectional view taken on the line 3—3 of Fig. 1, but with the carrier in its open position;

Fig. 4 is a side elevation of the carrier as folded;

Fig. 5 is a similar view taken on the plane indicated by the lines 5—5 of Fig. 2, and

Fig. 6 is a detail of a brace connection.

The luggage carrier of this invention includes mainly a bottom and a back, the former being permanently pivoted to the vehicle body while the latter may be removably braced thereagainst in its extended position although readily foldable with the bottom. The bottom 10 includes a pair of longitudinal members 11 which are connected by transverse end members 12, all of such members being formed from a suitable metallic material which need not be determined by the present invention, and in the angular cross sectional shape illustrated. The end members 12 are prolonged beyond that member 11 which is normally nearest to the vehicle body and are each pivoted through the medium of pins, rivets or the like fastening means 13 to a pair of ears 14 which are fastened directly to the vehicle back 15 by bolts 16 or a similar means of securement. Also connecting the frame members 11 are the slats 17 which are preferably thin but broad strips of metal upon which the luggage rests within the carrier.

The back 18 of the carrier includes a pair of longitudinal members 19 which parallel the members 11 and are similarly formed, while also connected by slats 17 which are preferably offset or staggered as regards the slats of the bottom 10 in order to prevent interference when the device is folded. A pair of securing ears 20 secured directly to the vehicle body 15 in the manner of the first mentioned ears 14 have pivoted thereto by a pin or stud 21, links 22 which have a similar connection 23 with the equivalent links 24, the opposite ends of which latter are pivoted by pins 25 to the outermost edge of the bottom 10, these pins also serving to pivotally connect the adjacent members 11 and 19 respectively of the bottom and back, providing for a folding movement of the latter over the former. When the device is extended the links 22 and 24 form a diagonal bracing connection for the bottom, although offering no obstruction to the ready folding of the carrier. The studs 21 which pass through the pivoting ears 20 are exteriorly formed with the enlarged heads 26 upon which may be locked the

back braces 27 when the carrier is in its extended position, such back braces being mounted for horizontal movement upon the upper face of one of the back members 19 and being intermediately twisted as denoted by the numeral 28 for proper engagement with the studs 26.

This engagement is preferably provided by the key-hole slot 29 formed in the locking extremity of each brace 27 in the inverted manner disclosed by Fig. 6 so that when the carrier is extended the weight of the braces 27 will normally tend to maintain them in their seated position. With the same studs 26 there is also adapted to coact the spring latches denoted 30 as an entirety which are pivoted at the outermost side of the bottom 10 directly to appropriate slats 17. The extremities 31 of each of these latches is angularly bent to extend into overlapping relationship with one of the ears 20 and is suitably slotted for engagement with the studs 21, when the carrier is folded as shown in Fig. 4. Springs 32 act in the obvious manner to resiliently resist disengagement of these latches, the path of movement of which is limited through the medium of the stirrups 33 shown in the drawings as being carried adjacent the outer extremities of the transverse bottom members 12. Yielding abutments 34 may be carried by the back of the vehicle body in order to contact with those portions of the carrier which would otherwise contact directly with the vehicle when folded, as the metal parts of the carrier might otherwise injure the highly polished finish of the automobile.

When the device is extended as in Fig. 3 and it is desired to have the parts assume their forward position, the braces 27 have their locking extremities disengaged with the stud 26 through the medium of the key-hole slot 29 and these braces are then folded back upon the uppermost side strip 19, the twisted portion 28 of each brace permitting it to overlap the adjacent brace in the manner shown in Fig. 1. The whole side 18 may now be folded down within the bottom 10 and it then remains but to fold this bottom upwardly upon the pivoting axis provided by the ears 14 and their pins 13 in order to enable the latches 30 to engage with the studs 21 in locking the carrier in the folded position shown in detail in Figs. 1, 4 and 5. It will be seen that a carrier of this description while amply braced and supported to maintain luggage of heavy descriptions, may be economically manufactured, may be placed upon a car or wagon without materially disfiguring the vehicle and may be readily folded or extended into the desired position.

While in the foregoing, however, there has thus been illustrated in the drawings and described in the specification such com-

bination and arrangement of elements as constitute the preferred embodiment of this invention, it is desired to emphasize the fact that such minor changes in the matters of proportion and degree may be made in later adaptations of this device as shall not alter the spirit of the invention as defined in the appended claims.

What is claimed is:—

1. The combination with a vehicle having 75 pairs of ears secured thereto, of a luggage carrier foldable upon itself and having permanent pivotal connections with one pair of ears, and connections pivoted to the foldable part of said carrier and disengageable from 80 the other pair of ears to permit folding of the carrier.

2. The combination with a vehicle having 85 pairs of ears secured thereto, of a foldable luggage carrier having permanent pivotal 85 connections with one pair of ears, and disengageable connections with the other pair, yielding abutments on said vehicle to prevent contact of said carrier, with the vehicle when folded, and means for locking the luggage carrier in folded position.

3. The combination with a vehicle having 95 pairs of ears secured thereto, of a luggage carrier including a bottom pivotally connected to one pair of ears, a back pivoted to 95 the bottom, and braces pivoted to the back and disengageably connected to the other pair of ears.

4. The combination with a vehicle having 100 pairs of ears secured thereto, of a luggage carrier including a bottom pivoted along one edge to one pair of ears, connections between the opposite edge of said bottom and the other ears, and a back having changeable connections with the last mentioned ears. 105

5. The combination with a vehicle having 110 pairs of ears secured thereto, of a luggage carrier including a bottom pivoted to one pair of ears, a back pivoted to said bottom, and braces pivoted to said back, for changeable connections with the other pair of ears.

6. The combination with a vehicle having 115 pairs of ears secured thereto, of a luggage carrier including a bottom pivoted to one pair of ears, a back pivoted to said bottom, braces pivoted to said back, changeable connections with the other pair of ears, and links pivotally connecting said bottom with the last mentioned ears.

7. The combination with a vehicle having 120 ears secured thereto in pairs, of a luggage carrier including a bottom pivoted to the lowermost pair of ears, a back pivoted to said bottom, means connected to said back for a bracing engagement with the uppermost ears, and means carried by said bottom for a locking engagement with said uppermost ears.

8. The combination with a vehicle provided with pairs of ears, of a luggage car- 125 130

rier including a bottom pivoted to the ears of one pair, linked means supporting said bottom from the upper pair of ears, a back foldably secured to said bottom, and latches carried by said bottom for resilient locking engagement with said second ears upon a folding of the device.

9. The combination with a vehicle having pairs of ears secured thereto, of a foldable luggage carrier including a bottom pivoted to the lowermost ears, a back pivoted to said bottom, braces pivoted to said back and having a locking engagement with the uppermost ears, linked connections directly between said uppermost ears and said bottom, and latch means carried by said bottom for a variable engagement with said uppermost ears when the carrier is folded.

10. The combination with a vehicle provided with ears in pairs, of a foldable luggage carrier including a bottom pivoted to one pair of ears, a back pivoted to said bottom, pairs of pivoted links supporting said bottom from the remaining ears, studs carried in said latter ears and formed with enlarged heads, braces pivoted to said back and provided with locking slots for a variable engagement with said studs when the carrier is extended, and latches carried by said bottom for engagement with said studs when the carrier is folded.

11. A luggage carrier for the purpose set forth comprising a bottom adapted to be pivoted to a vehicle, and a back pivotally connected to the outer edge of the bottom, said bottom including longitudinal members, end members connecting said longitudinal

members, and slats supported by said longitudinal members, said back being formed of longitudinal members and slats similarly connecting the longitudinal members thereof, and braces pivoted to the upper longitudinal back members for the purpose set forth.

12. A luggage carrier of the type described including longitudinal bottom members, longitudinal back members, connecting members for said bottom members, pivotal connections between an adjacent longitudinal member of both bottom and back, slats connecting the longitudinal members of both bottom and back, braces pivotally supported by one of the longitudinal back members, links pivoted in pairs to one of said bottom members, latches carried by certain of said bottom slat members, and locking studs for engagement with said braces or said latches.

13. The combination with a vehicle having supporting members mounted thereon, of a luggage carrier including a bottom pivoted to certain of said supporting members, a back pivoted to said bottom, bracing members connecting one edge of said bottom to the remaining supporting members, and changeable connections between one edge of said back and said remaining supporting members.

In testimony whereof I affix my signature in presence of two witnesses.
